MELVIN L. SCHAEFFER, OF WASHINGTON, DISTRICT OF COLUMBIA, ASSIGNOR OF ONE-HALF TO MUNSON H. LANE, OF WASHINGTON, DISTRICT OF COLUMBIA

SHOE-LACE TIP

Application filed November 29, 1930. Serial No. 499,068.

The invention relates to improvements in shoe-lace tips, and more particularly to the production of a simple and inexpensive tip, which may be cheaply and efficiently manufactured, and which may be readily applied to the shoe-lace.

A frequent cause of annoyance is the loss of the metal tip from a shoe-lace, and this is particularly troublesome in cases where new shoe-strings are not readily available. Accordingly the need exists for a shoe-lace tip which may be easily attached to a shoe-lace which has lost its tip, by the ordinary shoe-lace user and wearer. It is an object of the present invention to provide such a tip, which may either be applied by the manufacturer of the shoe-lace, or by the user in the event the original tip is lost. Other objects of the invention will appear herein-after.

According to the preferred embodiment of the invention, the tip comprises a metal shell within which a locking lever is pivotally mounted, which lever when in one position permits the insertion of a shoe-lace, but when in locked position firmly engages the lace preferably by means of a serrated jaw.

The invention will be more readily apparent from a consideration of the accompanying drawings and the following detailed description. It will be understood that the drawings set forth an illustrative embodiment of the inventive thought involved, but that the invention is not to be limited to the precise details of construction, as modifications and variations may be resorted to without departing from the spirit of the invention.

In the drawings,
Fig. 1 is a perspective view showing the tip applied to a shoe-lace;

Fig. 2 is a perspective view showing the parts of the tip, namely the shell and locking lever, separated preparatory to assembling the device;

Fig. 3 is a front view on an enlarged scale showing the serrated jaw of the locking lever;

Fig. 4 is a plan view of the blank from which the tip shell is formed; and

Fig. 5 is a similar view showing the blank from which the locking lever is formed.

Referring first to Fig. 1, showing the tip assembled upon the lace, the reference numeral 1 denotes a suitable lace, the end of which is adapted to be inserted into a frusto-conical shell 2, one side of which is provided with a substantially V-shaped opening 4, while adjacent this opening are apertures 3 formed in the wall of the tip to receive pintles 8 of a locking lever 5, shaped to substantially close the V-shaped opening 4. The locking lever 5 is provided with a serrated jaw 6 bent substantially at right angles to the handle of the lever. The jaw 6 is preferably provided with teeth 7 for gripping the shoe-lace when in locked position. To hold the lever in locked position an abutment lug 9 is formed on the tip shell partway across the V-shaped opening 4.

The tip shell 2 is preferably formed from a blank of sheet metal as indicated in Fig. 4, the sides of the blank being sloping, and the openings 3 formed in the wider portion of the blank, while the lug 9 projects from one of the sloping sides. The locking lever may be likewise formed from a single blank, as indicated in Fig. 5, which blank is substantially V-shaped in form, with the pintles 8 projecting from the sides of the V and with the teeth 7 formed at the upper edge. The shell 2 may be formed by rolling up its blank as indicated in Fig. 2, leaving the V-shaped opening 4 on one side of the completed frusto-conical shell. The locking lever is formed from its blank by bending the portion 6 along line 10 substantially at right angles to the arm of the lever. The locking lever may be assembled with the tip shell by forcing the sides of the V-shaped opening 4 slightly apart, which is readily accomplished due to

the resilience of the material from which the shell is composed, whereupon the pintles 8 are slipped into the apertures 3, and when the pressure on the sides of the V-shaped opening is released, the locking lever will be pivotally held in position within the top shell.

To permit the lace 1 to be inserted, the lever 5 is tilted upwardly so that the jaw 6 will be raised out of the way of the lace, the end of 10 which is pushed as far as possible into the conical shell. When the lace is in position the locking lever is lowered, whereupon the teeth 7 of the serrated jaw 6 firmly engage the lace and prevent its removal. The arm 15 of the lever 5 is held in position by inserting it beneath the lug 9, which may be accomplished by pressing the lever slightly to one side, which is possible on account of the resilient material employed in the shell and the lever, whereupon on releasing the pressure, 20 the lever snaps back into position and is firmly held beneath the lug. Alternatively, the lug 9 may be bent up out of the way of the lever 5 with the finger, to permit the lever to be pressed into locking position, whereupon 25 the lug 9 is bent down to overlie the lever, thus holding it firmly in position. If for any reason it should be desirable to remove the tip, this can be done by bending the lug 30 9 out of the way, whereupon the lever may be raised, releasing the shoe-string. This may be desirable where the shoe-string breaks and no other laces or tips are available. Under such circumstances, the old tip is removed 35 from the broken end of the shoe-string and replaced upon the remaining portion of the string.

What I claim is:

1. The combination with a shoe lace of a 40 detachable tip fitting over the end thereof, and of a size adapted to pass through the eyelets of a shoe, said tip comprising a shell reduced toward the tip end of the lace, and means for detachably locking the tip to the lace.

2. In combination with a shoe lace, a detachable tip fitting over the end thereof, of a size adapted to pass through the eyelets of a shoe, said tip comprising a shell reduced 50 toward the tip end of the lace, and means for detachably locking the tip to the lace, said means including a lever pivotally mounted within the shell and having a portion adapted to engage the shoe lace.

55 3. A shoe-lace tip or the like, comprising a shell adapted to receive the lace, means for locking the lace in the shell, the locking means including a lever pivotally mounted within the shell and having a portion adapted to engage the shoe-lace, and means for holding the locking lever in latched position.

4. A shoe-lace tip or the like, comprising a shell adapted to receive the lace, means for locking the lace in the shell, the locking means including a lever pivotally mounted

within the shell and having a portion adapted to engage the shoe-lace, and releasable means for holding the locking lever in latched position.

5. A shoe-lace tip or the like, comprising 70 a shell adapted to receive the lace, means for locking the lace in the shell, the locking means including a lever pivotally mounted within the shell and having a portion adapted to engage the shoe-lace, and means including a lug extending from the shell for holding the locking lever in latched position.

6. A shoe-lace tip or the like, comprising a frusto-conical metal shell adapted to receive 80 the end of a shoe-lace, said shell having V-shaped opening in one side, and a pair of apertures in the wall of the shell, one on each side of said V-shaped opening, and means for locking the lace within the shell, said means comprising a lever arm conforming 85 substantially in shape to said opening, having pintles on said arm engageable within the apertures in said shell, for pivotally mounting the locking lever, and a locking jaw carried by said lever and extending substantially at right angles thereto, said jaw having means for 90 engaging the shoe-lace when the lever is in latched position.

7. A shoe-lace tip or the like, comprising 95 a frusto-conical metal shell, adapted to receive the end of a shoe-lace, said shell having a V-shaped opening on one side, and a pair of apertures in the wall of the shell, one on each side of said V-shaped opening, and means for locking the lace within the shell, said means 100 comprising a lever arm conforming substantially in shape to said opening, having pintles on said arm engageable within the apertures in said shell, for pivotally mounting the locking lever, a locking jaw carried by said 105 lever and extending substantially at right angles thereto, said jaw having means for engaging the shoe-lace when the lever is in latched position, and means for holding said lever in latched position.

8. A shoe-lace tip or the like, comprising a frusto-conical metal shell adapted to receive the end of a shoe-lace, said shell having a V-shaped opening in one side, and a pair of apertures in the wall of the shell, one on each 115 side of said V-shaped opening, and means for locking the lace within the shell, said means comprising a lever arm conforming substantially in shape to said opening, having pintles on said arm engageable within the apertures in said shell, for pivotally mounting the locking lever, a locking jaw carried by said 120 lever and extending substantially at right angles thereto, said jaw having means for engaging the shoe-lace when the lever is in latched position, and releasable means for holding said lever in latched position.

9. A shoe-lace tip or the like, comprising 125 a frusto-conical metal shell adapted to receive the end of a shoe-lace, said shell having 130

a V-shaped opening in one side, and a pair of apertures in the wall of the shell, one on each side of the V-shaped opening, and means for locking the lace within the shell,
5 said means comprising a lever arm conforming substantially in shape to said opening, having pintles on said arm engageable with in the apertures in said shell, for pivotally mounting the locking lever, a locking jaw
10 carried by said lever and extending substantially at right angles thereto, said jaw having means for engaging the shoe-lace when the lever is in latched position, and means comprising a lug extending partially
15 across the V-shaped opening, for holding said lever in latched position.

In testimony whereof I affix my signature.
MELVIN L. SCHAEFFER.
